UNITED STATES PATENT OFFICE

156,335

RING BOX OR SIMILAR ARTICLE

Eleanor Groos, Mount Vernon, N. Y., assignor of twenty-five per cent to Milton Schaffer, twenty-five per cent to Harriet Schaffer, both of New York, N. Y., twenty-five per cent to Allan Schuander, and twenty-five per cent to Ruth Schuander, both of East Orange, N. J.

Application September 11, 1948, Serial No. 148,549

Term of patent 3½ years

(Cl. D80—5)

To all whom it may concern:

Be it known that I, Eleanor Groos, a citizen of the United States, residing at Mount Vernon, in the county of Westchester and State of New York, have invented a new, original, and ornamental Design for a Ring Box or Similar Article, of which the following is a specification, reference being had to the accompanying drawing, forming part thereof.

In the drawing:

Fig. 1 is a front elevational view of the ring box with its cover in open position, showing my new design;

Fig. 2 is a top view thereof with the cover in closed position.

Fig. 3 is a side elevational view thereof.

I claim:

The ornamental design for a ring box or similar article, as shown.

ELEANOR GROOS.
